(57) **CLAIM**

The ornamental design for an electronic training collar, as shown and described.

DESCRIPTION

FIG.1 is a top, front, left side perspective view of an electronic training collar, showing my new design;

FIG.2 is a bottom, front, right side perspective view thereof;

FIG.3 is a front elevation view thereof;

FIG.4 is a rear elevation view thereof;

FIG.5 is a left side elevation view thereof;

FIG.6 is a right side elevation view thereof;

FIG.7 is a top plan view thereof;

FIG.8 is a bottom plan view thereof;

FIG.9 is an enlarged partial rear elevation view of the electronic training collar, taken from the showing in FIG.4;

FIG.10 is an enlarged partial bottom plan view of the electronic training collar, taken from the showing in FIG.8;

FIG.11 is an enlarged partial front elevation view of the electronic training collar, taken from the showing in FIG.3;

FIG.12 is an enlarged partial top plan view of the electronic training collar, taken from the showing in FIG.7;

FIG.13 is an enlarged partial perspective view of the electronic training collar, taken from the showing in FIG.1;

FIG.14 is an enlarged left side elevation view thereof; and, FIG.15 is an enlarged right side perspective view thereof.

The broken lines depict portions of the article that form no part of the claimed design.

1 Claim, 15 Drawing Sheets
